UNITED STATES PATENT OFFICE

FRANK E. McCABE, OF CLEVELAND, OHIO, ASSIGNOR TO THE GRABLER MANUFACTURING COMPANY, OF CLEVELAND, OHIO, A CORPORATION OF OHIO

MEANS FOR TREATING MOLDING SAND

Application filed March 25, 1927. Serial No. 178,252.

This invention has to do, generally, with so-called "continuous" foundry systems, wherein quantity production and uniformity of product are the essential objectives. 5 In these systems, the molding sand is used over and over again, and the keeping of the sand in proper condition at all times has proven a difficult problem. This is of paramount importance, however, if castings of 10 high quality and uniform grade are to be produced.

It is to the sand treatment in systems of the class referred to that my invention particularly relates.

15 The retempering of the sand is effectively accomplished by reconditioning apparatus that is in more or less general use; but it was learned from experience that an essential quality was lacking from the molding sand when it was returned from the reconditioning apparatus to the flasks. This was due to the fact that the sand was continuously passed through a hopper or bin between the reconditioning apparatus and the 20 molding machine, and a considerable part of the sand would stick to the walls of the hopper or bin until it became so dry that it would cease to adhere to the walls and would fall in relatively large masses and be 25 carried with the fresh sand to the molding machines. This destroyed the uniform character of the sand and resulted in the production of weak and inferior molds.

The main object of my invention is to 30 provide a means and method for overcoming this difficulty in a simple, efficient and economical manner and without slowing down or interrupting the operation of the system.

35 An arrangement whereby this object is attained is illustrated diagrammatically in the accompanying drawings wherein Fig. 1 represents my improved sand handling and treating apparatus in side elevation; Fig. 2 represents an elevational view taken as though looking from the right of Fig. 1; and Fig. 3 is a sectional plan on the line 3-3 of Fig. 2.

Structural details have been omitted from 40 the drawings inasmuch as all the elements

shown are of well known construction, and practical proportions as to relative sizes of the several units of the system have been discarded in order to emphasize the method and more clearly set out the sand handling and treating apparatus to which the invention is restricted. 55

In foundry systems of the class referred to, there are mold forming, mold pouring, and shake-out stations, and mold or flask carriers are movable along a course or track through or past said stations, successively. An example of such a system may be found in my former application Serial No. 57,333, filed September 19, 1925. It will be seen by reference to said application that the sand is distributed by suitable conveyors from the sand reconditioning apparatus to the molding machines at the mold forming station, and the surplus sand is recovered from the mold forming station, and also from the shake-out station—where the castings and sand are separated—and returned to the reconditioning apparatus. The same arrangement is present in the case at hand. In Fig. 1 the mold forming station is represented by a molding machine that is designated A, and it will be noted that there is an opening *a* in the floor *a'* on which the molding machine stands through which surplus sand is adapted to fall to the lower horizontal run *b* of a flight conveyor that is designated generally by the reference letter B and which is of rectangular form and is disposed in a vertical plane. This flight conveyor is of standard construction and involves a series of scrapers *b'* which operate in troughs or casings. A belt conveyor C, which receives sand from the shake-out station or apparatus, also discharges onto the lower run *b* of the conveyor B and this sand, with that recovered from the molding station, is carried up the ascending run *b*³ to the upper horizontal run *b*⁴. The sand is 60 dumped through an opening *b*⁵ in the bottom of the trough of the upper run *b*⁴ into the sand reconditioning apparatus that is designated D, where new sand, binder, and moisture are added to the previously used 65

sand and the whole is thoroughly mixed and tempered.

The reconditioned sand is discharged from the apparatus D onto the lower run e of a second flight conveyor E which carries the sand up an ascending run e' to an upper horizontal run e². Disposed below this run are two bins or receivers F and G into which the sand is adapted to be discharged from the conveyor E. To this end openings e³ and e⁴ are made in the bottom of the trough of the upper run e² above the respective bins F and G, and the former opening is provided with a slide or gate e⁵. When this slide or gate is open, all the sand is discharged through the opening e³ into the bin F, but when the same is closed, the sand is carried past the opening e³ and is precipitated through the opening e⁴ into the bin G. The bottoms of the bins F and G are constituted of the respective belt conveyors f and g, the latter, when operating, discharging directly into the upper run b⁴ of the conveyor B, while the former conveyor f, when operating, discharges onto a similar conveyor f' which is arranged transversely of the conveyor f and has its discharge end in delivering relation to the upper run of the conveyor E in advance of the discharge point of the conveyor g.

It will be observed that, as the parts are illustrated, the slide or gate e⁵ is closed and that the flight conveyor E is discharging the reconditioned sand into the bin G. While the bin G is thus being filled, the bin F is being emptied by reason of the fact that the conveyors f and f' are in operation which causes the sand from the bin F to be carried by the conveyors just mentioned and along the upper run b⁴ of the conveyor B to a chute b⁶ that leads to the mold forming station represented by the molding machine A.

As the supply of sand within the bin F is exhausted, the belt conveyor g is set in operation, the conveyors f and f' are stopped, and the slide or gate e⁵ is opened, whereupon the sand from the reconditioning apparatus will be delivered to the bin F wherein it will accumulate until said bin is filled and while the bin G is being emptied.

By reason of this arrangement it will be seen that each bin is entirely emptied before any more sand is dumped into it, wherefore the sand adjacent the walls of the bin, and which has a tendency to adhere to said walls, is not permitted to remain in such inert condition long enough to become dry. And the withdrawing of the sand alternately from the two bins at comparatively brief intervals insures sand of uniform quality being delivered to the molding machines at all times.

It will be understood that suitable driving mechanisms (not shown) are employed for

operating the several conveyors, and the same may be supplied according to common mechanical practice.

Having thus described my invention, what I claim is:

1. In foundry apparatus wherein sand is separated from castings, reconditioned and returned to a hopper at a molding station, a plurality of storage tanks adapted to hold reconditioned sand, means for selectively filling said tanks and means for selectively emptying said tanks into said hopper, said means and said tanks being so arranged that the sand delivery is substantially continuous and caking and drying of reconditioned sand is prevented. 76

2. In foundry apparatus wherein sand is separated from castings at shake-out stations, re-conditioned and returned to a hopper at the molding station, re-conditioning apparatus, a conveyor adapted to deliver used sand to said apparatus, a plurality of storage tanks, a conveyor for selectively delivering sand from said re-conditioning means to said storage tanks, means for selectively discharging said storage tanks into said hopper, said conveyors, tanks and means being so arranged that the sand delivery is substantially continuous and caking and drying of re-conditioned sand is prevented. 80 85 90

In testimony whereof, I hereunto affix my signature.

FRANK E. McCABE.
